UNITED STATES PATENT OFFICE.

WILLIAM I. BUNKER, OF LA GRANGE, ILLINOIS.

DESIGN FOR A SWING-BRACKET FOR ROCKING-CHAIRS.

SPECIFICATION forming part of Design No. 24,928, dated November 26, 1895.

Application filed November 6, 1894. Serial No. 528,094. Term of patent 7 years.

To all whom it may concern:

Be it known that I, WILLIAM I. BUNKER, of La Grange, Illinois, have invented and produced a new and original Design for Swing-
5 Brackets for Rocking-Chairs, reference being had to the accompanying drawings, forming part hereof.

In the accompanying drawings, Figure 1 represents a perspective view of my design, 10 and Fig. 2 a cross-section taken on the line 2 of Fig. 1.

The leading feature of my design consists in a grooved or channel-shaped body portion provided with a semicircular hub, slightly 15 nearer one end, and two cylindrical bearing portions.

A is the body portion of the bracket, which is substantially **U**-shaped in contour and **I**-shaped in cross-section. B B are bearing portions by which it may be fastened to the 20 chair, and C a semicylindrical hub for the purpose of uniting two or more of the brackets together, the whole presenting to the eye a harmonious and ornate figure, substantially the same as that illustrated in the drawings. 25

I claim—

The design for a swing bracket for rocking chairs herein shown and described.

WILLIAM I. BUNKER.
